US0D1095276S

(12) **United States Design Patent** (10) **Patent No.:** **US D1,095,276 S**
(45) **Date of Patent:** **** Sep. 30, 2025**

(54) **SMOKE LEAK DETECTOR**

(71) Applicant: **Zhuhai Jiahao Technology Co., Ltd,**
Guangdong (CN)

(72) Inventor: **Shuiwen Chen**, Guangdong (CN)

(73) Assignee: **Zhuhai Jiahao Technology Co., Ltd,**
Zhuhai (CN)

(*) Notice: Patent file contains an affidavit/declaration
under 37 CFR 1.130(b).

(**) Term: **15 Years**

(21) Appl. No.: **29/980,662**

(22) Filed: **Dec. 26, 2024**

(51) LOC (15) Cl. **10-05**

(52) U.S. Cl. **D10/106.2**
USPC .....

(58) **Field of Classification Search**

USPC D10/46, 104.1, 106.2–106.5
CPC G01M 3/007; G01M 3/3254
See application file for complete search history.

(57) **CLAIM**

The ornamental design for a smoke leak detector as shown and described.

DESCRIPTION

FIG. 1 is a perspective view of a smoke leak detector showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.

The broken lines depict portions of the smoke leak detector and form no part of the claimed design.
